UNITED STATES PATENT OFFICE

105,823

DESIGN FOR A RESORT BUILDING

Herman E. Olson, Seattle, Wash.

Application April 23, 1937, Serial No. 68,957

Term of patent 14 years

To all whom it may concern:

Be it known that I, Herman E. Olson, a citizen of the United States, residing at Seattle, King County, Washington, have invented a new, original, and ornamental Design for Resort Buildings, of which the following is a specification, reference being had to the accompanying drawing, forming part thereof, wherein—

Fig. 1 is a front elevation of a resort building embodying the present design.

Fig. 2 is a plan view of the same.

I claim:

The ornamental design for a resort building, as shown.

HERMAN E. OLSON.
